2,600,793

CORE-SUPPLYING MEANS FOR WINDING MACHINES

John A. Molloy, Warwick, R. I., assignor to Universal Winding Company, Boston, Mass., a corporation of Massachusetts

Application June 17, 1946, Serial No. 677,186

32 Claims. (Cl. 242—35.5)

1

This invention relates to winding machines and particularly to means for supplying bare cores such as wooden bobbins or the like to the magazines of a plurality of automatic winding units arranged in multiple or gang form.

As herein shown and described the core-delivering means is adapted for replenishing the supply of cores or bobbins in the magazine of an automatic winding machine operating to continuously produce wound bobbins for the shuttles of looms. It is to be understood, however, that the present invention may be used for supplying other types of cores to winding machines for producing different types of wound packages. The term "wound bobbin" as hereinafter used is therefore intended to include any conventional type of package or wound mass of yarn and the term "yarn" is intended to indicate all kinds of strand materials, either textile or otherwise.

One object of the present invention is to provide automatically-operated core-supplying means comprising a bin or hopper for containing a large number of bare cores indiscriminately or randomly disposed therein with means for feeding the cores from the hopper to a conveyor and distributing them to the magazines of a plurality of winding units when the supply therein is depleted.

Another object is to provide means at the hopper for selectively feeding the cores to the conveying means as required by the discharge therefrom of any of the cores into the magazines of the winding units.

Another object is to provide means cooperating with the individual magazines for indicating depletion of the supply of cores therein and replenishing the supply by delivery of fresh cores thereto.

Another object is to provide a traveling conveyor-belt or -chain having pockets for receiving the cores and means for filling the pockets from the supply in the hopper as the pockets become vacant due to the delivery of their cores to the magazines.

Another object is to provide means normally restrained from action when the magazines of the winding units contain a sufficient supply of cores and operative upon depletion of the supply to actuate the means for delivering fresh cores thereto.

A principal object of the invention is to render the core-supplying and -delivering means entirely automatic, thereby eliminating all manual operations except to dump the cores into the hopper.

Further objects and advantages of the inven-

2

tion are set forth in the following specification which describes a preferred form of construction of the apparatus, including modifications in certain of its details, as illustrated by the accompanying drawings. In the drawings:

Fig. 1 is a front elevational view showing a portion of a series of winding units mounted on a bed or frame, broken away at the center, and illustrating the present improved core-supplying means as applied to use therewith;

Fig. 2 is an enlarged end elevation of the same, part-sectional on line 2—2 of Fig. 1, showing the essential elements of a single winding unit and a portion of the core-supplying means for cooperation therewith;

Fig. 3 is a similar view of the machine shown partly in section with the depletion-indicating lever or detector for the magazine in released position for delivering a fresh bobbin to the magazine;

Fig. 4 is a fragmentary detailed view of the same showing the parts in different position;

Fig. 5 is a partial plan view of the conveyor-chain and the core-delivering means;

Fig. 6 is a detailed fragmentary view of the same showing the parts in different position;

Fig. 7 is a view similar to Fig. 5 with the delivering means shown in different position;

Fig. 8 is a fragmentary detailed view of the same;

Fig. 9 is a perspective view of one of the socketed bobbin-holders on the conveyor-chain;

Fig. 10 is a view similar to Fig. 3 illustrating a modified form of the core-delivering means;

Figs. 11 to 15, inclusive, are views similar to Figs. 4 to 8, inclusive, showing the relationship of the parts of the core-delivering means in the modified form illustrated in Fig. 10;

Fig. 16 is a perspective view of the detent-means for relaying the action of the core-delivering means until one core has passed thereby;

Fig. 17 is a side elevation of the forward end of the core- or bobbin-supply hopper showing the selector-mechanism for feeding cores to the empty pockets of the conveyor-chain;

Fig. 18 is an enlarged plan view of the selector-mechanism shown with its parts in inactive relationship;

Fig. 19 is a side elevation of the same;

Fig. 20 is an enlarged plan view similar to Fig. 18 showing the parts of the selector-mechanism operative to insert an empty core into one of the pockets of the conveyor-chain; and

Fig. 21 is a fragmentary plan view of the same

showing the parts in the same relation as that illustrated in Fig. 20.

Recent developments in the textile field have for their object to render the machines employed therein highly automatic in operation and in the winding art the production of wound bobbins, cops, and various forms of packages has been rendered partly automatic by providing magazines for the empty cores, means for transferring the cores therefrom and donning them on the winding spindles, doffing the wound packages from the machine; and, in most instances, providing a continuous supply of yarn for delivery to the winding packages. Such a type of automatic machine is shown and described in United States Letters Patent No. 2,302,715, dated November 24, 1942, wherein the cores or wooden bobbins are placed in a magazine at each winding unit and transferred individually to, and donned on, the winding spindles upon doffing of the wound bobbins therefrom. Figs. 1 and 2 of the present drawings illustrate a machine of this type wherein a plurality of tapered cores or bobbins *b*, of wood, paper or other suitable material, are contained in a magazine *2* and transferred therefrom as required to the winding spindle *3* upon the completion and doffing of each wound bobbin or package. The winding spindle *3* is journaled in bearings in a frame or casing *4* containing the gearing and other parts of the driving mechanism of the machine unit. The magazine *2* may comprise two slotted uprights *5* and *6* supported in opposed relationship at the front of the winding unit with the part *5* adapted to hold the enlarged end or head *h* of the core *b*; the cores being delivered from the bottom of the magazine by suitable transfer means shown and described in the patent referred to above but not herein illustrated in detail. The cores or bobbins *b* are held between a driver *7* at the end of the spindle *3* and the cupped end of an outboard stub-spindle *8*; one or the other of these holding means being retractible when the winding is completed to doff the wound bobbin for discharging it from the machine. As each wound package is doffed from the winding spindle a fresh core or bobbin *b* is fed from the magazine *2* and transferred into position to be gripped between the rotary elements *7* and *8*, all as explained more fully in the patent referred to above.

During the winding of the bobbins in the machine, yarn is supplied thereto from relatively large packages such as the cones *C* and *C'*, illustrated in Figs. 1 and 2, the yarn strand delivering from the forward cone *C* through a tension device, indicated generally at *T*, and thence feeding down to a traversing thread-guide, not herein shown, which distributes it on the core *b* in crossing coils which build up the wound bobbin shown at *B* in Fig. 2 as partly completed. The yarn supplies or cones *C*, *C'* are "magazined" on a creel with the trailing end of the first delivering package *C* united to the leading end of the reserve package *C'* so that upon exhaustion of the yarn in the first supply *C* the strand will deliver from the reserve supply *C'*. By this arrangement a large amount of yarn is provided for continuous delivery to wind the relatively small bobbins or packages *B* at each spindle and the operator is allowed plenty of time to tie in new cones or packages upon the exhaustion of any of them without interrupting the winding operation. However, since the winding packages or bobbins

B hold a relatively small amount of yarn, the empty cores or bare bobbins *b* must be furnished to the high-speed winding spindles at very frequent intervals and this requires continuous replenishment of the magazines *2*. That is to say, the magazines are necessarily limited as to the number of cores or bobbins which can be contained therein and therefore a considerable expenditure of time and effort is required of the operator to maintain the magazines filled at all of the units of a multi-spindle machine.

The present invention provides automatically-operated means for maintaining the continuous delivery of cores or empty bobbins to the magazines of a multi-spindle machine comprising a large number of units as the supply of cores becomes depleted in the magazines. In general, the present apparatus comprises a hopper or bin for holding a large supply of cores, usually several hundred in number; means for feeding the cores from the hopper in a procession; a conveyor for traveling the cores to their destination at the several winding units; means for discharging the cores from the conveyor and delivering them into the magazines as the supplies of cores therein become depleted; and means for selectively feeding new cores from the hopper to the conveyor as the first-conveyed cores are discharged therefrom.

The yarn-supply cones *C*, *C'* are mounted on holders comprising disks *10* supported from a skeleton framework forming the creel. As shown more particularly in Fig. 2, the creel framework may consist of a series of inverted U-shaped brackets *11* resting on the sides of the box-like casings *4* of certain of the units. Rising from the U-shaped brackets *11* are a series of inclined arms *12* forming part of the support for V-shaped bent rods *13*, the opposite vertical ends of which are held in the brackets. The magazines *2* for the cores or empty bobbins *b* may also be supported from the brackets *11*, these connections not being herein shown in detail as they are illustrated in the patent referred to above. The rods or stanchions *13* also form the support for a series of horizontal crossarms *14* in the form of angle-irons which carry a pair of tracks *15* for the conveyor-chain *20*. The tracks *15* are of hollow construction with circular runways at top and bottom and extend horizontally in straight stretches along opposite sides of the gang machine. The traveling conveyor may be in the form of a belt or a chain *20* of any usual construction comprising pivoted links *21* as shown in Figs. 18 and 20 with rollers *22* and *23* which ride in the curved runways of the tracks *15*. The lower roller *22* rides in the bottom runway of the hollow track *15* to take the weight of the chain *20* and the upper roller *23* travels along the sides of the runway of the track to prevent lateral motion of the chain. The chain *20* engages with the teeth of four sprockets *24* and *25*, see Figs. 1 and 20, supported at the four corners of the framework which surmounts the gang machine, the sprocket *24* being shown in Fig. 1 as journaled in a bearing *26* on a bracket *28* fastened to the top of a vertical rod or stanchion *29* supported from the bed of the machine. At the opposite end of the machine bed is a similar stanchion *30* supporting a bracket *31* carrying a bearing *32* for the sprocket *25*, these supports and sprockets being duplicated at the back of the machine. The sprocket *24* is driven from a shaft *33* carrying a bevel-gear *34* at its lower end in mesh with a bevel-gear *35* fast on a horizontal shaft *36* journaled in a bearing *37* on a bracket *38* fastened to the top of a vertical rod or stanchion *39* supported from the bed of the machine. The bevel-gear *35* drives a bevel-gear *40* on a horizontal shaft *41* journaled in a bearing *42* on a bracket *43* fastened to the top of a vertical rod or stanchion *44* supported from the bed of the machine. The bevel-gear *40* drives a bevel-gear *45* on a horizontal shaft *46* journaled in a bearing *47* on a bracket *48* fastened to the top of a vertical rod or stanchion *49* supported from the bed of the machine. The bevel-gear *45* drives a bevel-gear *50* on a horizontal shaft *51* journaled in a bearing *52* on a bracket *53* fastened to the top of a vertical rod or stanchion *54* supported from the bed of the machine. The bevel-gear *50* drives a bevel-gear *55* on a horizontal shaft *56* journaled in a bearing *57* on a bracket *58* fastened to the top of a vertical rod or stanchion *59* supported from the bed of the machine. The bevel-gear *55* drives a bevel-gear *60* on a horizontal shaft *61* journaled in a bearing *62* on a bracket *63* fastened to the top of a vertical rod or stanchion *64* supported from the bed of the machine. The bevel-gear *60* drives a bevel-gear *65* on a horizontal shaft *66* journaled in a bearing *67* on a bracket *68* fastened to the top of a vertical rod or stanchion *69* supported from the bed of the machine. The bevel-gear *65* drives a bevel-gear *70* on a horizontal shaft *71* journaled in a bearing *72* on a bracket *73* fastened to the top of a vertical rod or stanchion *74* supported from the bed of the machine. The bevel-gear *70* drives a bevel-gear *75* on a horizontal shaft *76* journaled in a bearing *77* on a bracket *78* fastened to the top of a vertical rod or stanchion *79* supported from the bed of the machine. The bevel-gear *75* drives a bevel-gear *80* on a horizontal shaft *81* journaled in a bearing *82* on a bracket *83* fastened to the top of a vertical rod or stanchion *84* supported from the bed of the machine. The bevel-gear *80* drives a bevel-gear *85* on a horizontal shaft *86* journaled in a bearing *87* on a bracket *88* fastened to the top of a vertical rod or stanchion *89* supported from the bed of the machine. The bevel-gear *85* drives a bevel-gear *90* on a horizontal shaft *91* journaled in a bearing *92* on a bracket *93* fastened to the top of a vertical rod or stanchion *94* supported from the bed of the machine. The bevel-gear *90* drives a bevel-gear *95* on a horizontal shaft *96* journaled in a bearing *97* on a bracket *98* fastened to the top of a vertical rod or stanchion *99* supported from the bed of the machine. The bevel-gear *95* drives a bevel-gear *100* on a horizontal shaft *101* journaled in a bearing *102* on a bracket *103* fastened to the top of a vertical rod or stanchion *104* supported from the bed of the machine. The bevel-gear *100* drives a bevel-gear *105* on a horizontal shaft *106* journaled in a bearing *107* on a bracket *108* fastened to the top of a vertical rod or stanchion *109* supported from the bed of the machine. The bevel-gear *105* drives a bevel-gear *110* on a horizontal shaft *111* journaled in a bearing *112* on a bracket *113* fastened to the top of a vertical rod or stanchion *114* supported from the bed of the machine. The bevel-gear *110* drives a bevel-gear *115* on a horizontal shaft *116* journaled in a bearing *117* on a bracket *118* fastened to the top of a vertical rod or stanchion *119* supported from the bed of the machine. The bevel-gear *115* drives a bevel-gear *120* on a horizontal shaft *121* journaled in a bearing *122* on a bracket *123* fastened to the top of a vertical rod or stanchion *124* supported from the bed of the machine. The bevel-gear *120* drives a bevel-gear *125* on a horizontal shaft *126* journaled in a bearing *127* on a bracket *128* fastened to the top of a vertical rod or stanchion *129* supported from the bed of the machine. The bevel-gear *125* drives a bevel-gear *130* on a horizontal shaft *131* journaled in a bearing *132* on a bracket *133* fastened to the top of a vertical rod or stanchion *134* supported from the bed of the machine. The bevel-gear *130* drives a bevel-gear *135* on a horizontal shaft *136* journaled in a bearing *137* on a bracket *138* fastened to the top of a vertical rod or stanchion *139* supported from the bed of the machine. The bevel-gear *135* drives a bevel-gear *140* on a horizontal shaft *141* journaled in a bearing *142* on a bracket *143* fastened to the top of a vertical rod or stanchion *144* supported from the bed of the machine. The bevel-gear *140* drives a bevel-gear *145* on a horizontal shaft *146* journaled in a bearing *147* on a bracket *148* fastened to the top of a vertical rod or stanchion *149* supported from the bed of the machine. The bevel-gear *145* drives a bevel-gear *150* on a horizontal shaft *151* journaled in a bearing *152* on a bracket *153* fastened to the top of a vertical rod or stanchion *154* supported from the bed of the machine. The bevel-gear *150* drives a bevel-gear *155* on a horizontal shaft *156* journaled in a bearing *157* on a bracket *158* fastened to the top of a vertical rod or stanchion *159* supported from the bed of the machine. The bevel-gear *155* drives a bevel-gear *160* on a horizontal shaft *161* journaled in a bearing *162* on a bracket *163* fastened to the top of a vertical rod or stanchion *164* supported from the bed of the machine. The bevel-gear *160* drives a bevel-gear *165* on a horizontal shaft *166* journaled in a bearing *167* on a bracket *168* fastened to the top of a vertical rod or stanchion *169* supported from the bed of the machine. The bevel-gear *165* drives a bevel-gear *170* on a horizontal shaft *171* journaled in a bearing *172* on a bracket *173* fastened to the top of a vertical rod or stanchion *174* supported from the bed of the machine. The bevel-gear *170* drives a bevel-gear *175* on a horizontal shaft *176* journaled in a bearing *177* on a bracket *178* fastened to the top of a vertical rod or stanchion *179* supported from the bed of the machine. The bevel-gear *175* drives a bevel-gear *180* on a horizontal shaft *181* journaled in a bearing *182* on a bracket *183* fastened to the top of a vertical rod or stanchion *184* supported from the bed of the machine. The bevel-gear *180* drives a bevel-gear *185* on a horizontal shaft *186* journaled in a bearing *187* on a bracket *188* fastened to the top of a vertical rod or stanchion *189* supported from the bed of the machine. The bevel-gear *185* drives a bevel-gear *190* on a horizontal shaft *191* journaled in a bearing *192* on a bracket *193* fastened to the top of a vertical rod or stanchion *194* supported from the bed of the machine. The bevel-gear *190* drives a bevel-gear *195* on a horizontal shaft *196* journaled in a bearing *197* on a bracket *198* fastened to the top of a vertical rod or stanchion *199* supported from the bed of the machine. The bevel-gear *195* drives a bevel-gear *200* on a horizontal shaft *201* journaled in a bearing *202* on a bracket *203* fastened to the top of a vertical rod or stanchion *204* supported from the bed of the machine. The bevel-gear *200* drives a bevel-gear *205* on a horizontal shaft *206* journaled in a bearing *207* on a bracket *208* fastened to the top of a vertical rod or stanchion *209* supported from the bed of the machine. The bevel-gear *205* drives a bevel-gear *210* on a horizontal shaft *211* journaled in a bearing *212* on a bracket *213* fastened to the top of a vertical rod or stanchion *214* supported from the bed of the machine. The bevel-gear *210* drives a bevel-gear *215* on a horizontal shaft *216* journaled in a bearing *217* on a bracket *218* fastened to the top of a vertical rod or stanchion *219* supported from the bed of the machine. The bevel-gear *215* drives a bevel-gear *220* on a horizontal shaft *221* journaled in a bearing *222* on a bracket *223* fastened to the top of a vertical rod or stanchion *224* supported from the bed of the machine. The bevel-gear *220* drives a bevel-gear *225* on a horizontal shaft *226* journaled in a bearing *227* on a bracket *228* fastened to the top of a vertical rod or stanchion *229* supported from the bed of the machine. The bevel-gear *225* drives a bevel-gear *230* on a horizontal shaft *231* journaled in a bearing *232* on a bracket *233* fastened to the top of a vertical rod or stanchion *234* supported from the bed of the machine. The bevel-gear *230* drives a bevel-gear *235* on a horizontal shaft *236* journaled in a bearing *237* on a bracket *238* fastened to the top of a vertical rod or stanchion *239* supported from the bed of the machine. The bevel-gear *235* drives a bevel-gear *240* on a horizontal shaft *241* journaled in a bearing *242* on a bracket *243* fastened to the top of a vertical rod or stanchion *244* supported from the bed of the machine. The bevel-gear *240* drives a bevel-gear *245* on a horizontal shaft *246* journaled in a bearing *247* on a bracket *248* fastened to the top of a vertical rod or stanchion *249* supported from the bed of the machine. The bevel-gear *245* drives a bevel-gear *250* on a horizontal shaft *251* journaled in a bearing *252* on a bracket *253* fastened to the top of a vertical rod or stanchion *254* supported from the bed of the machine. The bevel-gear *250* drives a bevel-gear *255* on a horizontal shaft *256* journaled in a bearing *257* on a bracket *258* fastened to the top of a vertical rod or stanchion *259* supported from the bed of the machine. The bevel-gear *255* drives a bevel-gear *260* on a horizontal shaft *261* journaled in a bearing *262* on a bracket *263* fastened to the top of a vertical rod or stanchion *264* supported from the bed of the machine. The bevel-gear *260* drives a bevel-gear *265* on a horizontal shaft *266* journaled in a bearing *267* on a bracket *268* fastened to the top of a vertical rod or stanchion *269* supported from the bed of the machine. The bevel-gear *265* drives a bevel-gear *270* on a horizontal shaft *271* journaled in a bearing *272* on a bracket *273* fastened to the top of a vertical rod or stanchion *274* supported from the bed of the machine. The bevel-gear *270* drives a bevel-gear *275* on a horizontal shaft *276* journaled in a bearing *277* on a bracket *278* fastened to the top of a vertical rod or stanchion *279* supported from the bed of the machine. The bevel-gear *275* drives a bevel-gear *280* on a horizontal shaft *281* journaled in a bearing *282* on a bracket *283* fastened to the top of a vertical rod or stanchion *284* supported from the bed of the machine. The bevel-gear *280* drives a bevel-gear *285* on a horizontal shaft *286* journaled in a bearing *287* on a bracket *288* fastened to the top of a vertical rod or stanchion *289* supported from the bed of the machine. The bevel-gear *285* drives a bevel-gear *290* on a horizontal shaft *291* journaled in a bearing *292* on a bracket *293* fastened to the top of a vertical rod or stanchion *294* supported from the bed of the machine. The bevel-gear *290* drives a bevel-gear *295* on a horizontal shaft *296* journaled in a bearing *297* on a bracket *298* fastened to the top of a vertical rod or stanchion *299* supported from the bed of the machine. The bevel-gear *295* drives a bevel-gear *300* on a horizontal shaft *301* journaled in a bearing *302* on a bracket *303* fastened to the top of a vertical rod or stanchion *304* supported from the bed of the machine. The bevel-gear *300* drives a bevel-gear *305* on a horizontal shaft *306* journaled in a bearing *307* on a bracket *308* fastened to the top of a vertical rod or stanchion *309* supported from the bed of the machine. The bevel-gear *305* drives a bevel-gear *310* on a horizontal shaft *311* journaled in a bearing *312* on a bracket *313* fastened to the top of a vertical rod or stanchion *314* supported from the bed of the machine. The bevel-gear *310* drives a bevel-gear *315* on a horizontal shaft *316* journaled in a bearing *317* on a bracket *318* fastened to the top of a vertical rod or stanchion *319* supported from the bed of the machine. The bevel-gear *315* drives a bevel-gear *320* on a horizontal shaft *321* journaled in a bearing *322* on a bracket *323* fastened to the top of a vertical rod or stanchion *324* supported from the bed of the machine. The bevel-gear *320* drives a bevel-gear *325* on a horizontal shaft *326* journaled in a bearing *327* on a bracket *328* fastened to the top of a vertical rod or stanchion *329* supported from the bed of the machine. The bevel-gear *325* drives a bevel-gear *330* on a horizontal shaft *331* journaled in a bearing *332* on a bracket *333* fastened to the top of a vertical rod or stanchion *334* supported from the bed of the machine. The bevel-gear *330* drives a bevel-gear *335* on a horizontal shaft *336* journaled in a bearing *337* on a bracket *338* fastened to the top of a vertical rod or stanchion *339* supported from the bed of the machine. The bevel-gear *335* drives a bevel-gear *340* on a horizontal shaft *341* journaled in a bearing *342* on a bracket *343* fastened to the top of a vertical rod or stanchion *344* supported from the bed of the machine. The bevel-gear *340* drives a bevel-gear *345* on a horizontal shaft *346* journaled in a bearing *347* on a bracket *348* fastened to the top of a vertical rod or stanchion *349* supported from the bed of the machine. The bevel-gear *345* drives a bevel-gear *350* on a horizontal shaft *351* journaled in a bearing *352* on a bracket *353* fastened to the top of a vertical rod or stanchion *354* supported from the bed of the machine. The bevel-gear *350* drives a bevel-gear *355* on a horizontal shaft *356* journaled in a bearing *357* on a bracket *358* fastened to the top of a vertical rod or stanchion *359* supported from the bed of the machine. The bevel-gear *355* drives a bevel-gear *360* on a horizontal shaft *361* journaled in a bearing *362* on a bracket *363* fastened to the top of a vertical rod or stanchion *364* supported from the bed of the machine. The bevel-gear *360* drives a bevel-gear *365* on a horizontal shaft *366* journaled in a bearing *367* on a bracket *368* fastened to the top of a vertical rod or stanchion *369* supported from the bed of the machine. The bevel-gear *365* drives a bevel-gear *370* on a horizontal shaft *371* journaled in a bearing *372* on a bracket *373* fastened to the top of a vertical rod or stanchion *374* supported from the bed of the machine. The bevel-gear *370* drives a bevel-gear *375* on a horizontal shaft *376* journaled in a bearing *377* on a bracket *378* fastened to the top of a vertical rod or stanchion *379* supported from the bed of the machine. The bevel-gear *375* drives a bevel-gear *380* on a horizontal shaft *381* journaled in a bearing *382* on a bracket *383* fastened to the top of a vertical rod or stanchion *384* supported from the bed of the machine. The bevel-gear *380* drives a bevel-gear *385* on a horizontal shaft *386* journaled in a bearing *387* on a bracket *388* fastened to the top of a vertical rod or stanchion *389* supported from the bed of the machine. The bevel-gear *385* drives a bevel-gear *390* on a horizontal shaft *391* journaled in a bearing *392* on a bracket *393* fastened to the top of a vertical rod or stanchion *394* supported from the bed of the machine. The bevel-gear *390* drives a bevel-gear *395* on a horizontal shaft *396* journaled in a bearing *397* on a bracket *398* fastened to the top of a vertical rod or stanchion *399* supported from the bed of the machine. The bevel-gear *395* drives a bevel-gear *400* on a horizontal shaft *401* journaled in a bearing *402* on a bracket *403* fastened to the top of a vertical rod or stanchion *404* supported from the bed of the machine. The bevel-gear *400* drives a bevel-gear *405* on a horizontal shaft *406* journaled in a bearing *407* on a bracket *408* fastened to the top of a vertical rod or stanchion *409* supported from the bed of the machine. The bevel-gear *405* drives a bevel-gear *410* on a horizontal shaft *411* journaled in a bearing *412* on a bracket *413* fastened to the top of a vertical rod or stanchion *414* supported from the bed of the machine. The bevel-gear *410* drives a bevel-gear *415* on a horizontal shaft *416* journaled in a bearing *417* on a bracket *418* fastened to the top of a vertical rod or stanchion *419* supported from the bed of the machine. The bevel-gear *415* drives a bevel-gear *420* on a horizontal shaft *421* journaled in a bearing *422* on a bracket *423* fastened to the top of a vertical rod or stanchion *424* supported from the bed of the machine. The bevel-gear *420* drives a bevel-gear *425* on a horizontal shaft *426* journaled in a bearing *427* on a bracket *428* fastened to the top of a vertical rod or stanchion *429* supported from the bed of the machine. The bevel-gear *425* drives a bevel-gear *430* on a horizontal shaft *431* journaled in a bearing *432* on a bracket *433* fastened to the top of a vertical rod or stanchion *434* supported from the bed of the machine. The bevel-gear *430* drives a bevel-gear *435* on a horizontal shaft *436* journaled in a bearing *437* on a bracket *438* fastened to the top of a vertical rod or stanchion *439* supported from the bed of the machine. The bevel-gear *435* drives a bevel-gear *440* on a horizontal shaft *441* journaled in a bearing *442* on a bracket *443* fastened to the top of a vertical rod or stanchion *444* supported from the bed of the machine. The bevel-gear *440* drives a bevel-gear *445* on a horizontal shaft *446* journaled in a bearing *447* on a bracket *448* fastened to the top of a vertical rod or stanchion *449* supported from the bed of the machine. The bevel-gear *445* drives a bevel-gear *450* on a horizontal shaft *451* journaled in a bearing *452* on a bracket *453* fastened to the top of a vertical rod or stanchion *454* supported from the bed of the machine. The bevel-gear *450* drives a bevel-gear *455* on a horizontal shaft *456* journaled in a bearing *457* on a bracket *458* fastened to the top of a vertical rod or stanchion *459* supported from the bed of the machine. The bevel-gear *455* drives a bevel-gear *460* on a horizontal shaft *461* journaled in a bearing *462* on a bracket *463* fastened to the top of a vertical rod or stanchion *464* supported from the bed of the machine. The bevel-gear *460* drives a bevel-gear *465* on a horizontal shaft *466* journaled in a bearing *467* on a bracket *468* fastened to the top of a vertical rod or stanchion *469* supported from the bed of the machine. The bevel-gear *465* drives a bevel-gear *470* on a horizontal shaft *471* journaled in a bearing *472* on a bracket *473* fastened to the top of a vertical rod or stanchion *474* supported from the bed of the machine. The bevel-gear *470* drives a bevel-gear *475* on a horizontal shaft *476* journaled in a bearing *477* on a bracket *478* fastened to the top of a vertical rod or stanchion *479* supported from the bed of the machine. The bevel-gear *475* drives a bevel-gear *480* on a horizontal shaft *481* journaled in a bearing *482* on a bracket *483* fastened to the top of a vertical rod or stanchion *484* supported from the bed of the machine. The bevel-gear *480* drives a bevel-gear *485* on a horizontal shaft *486* journaled in a bearing *487* on a bracket *488* fastened to the top of a vertical rod or stanchion *489* supported from the bed of the machine. The bevel-gear *485* drives a bevel-gear *490* on a horizontal shaft *491* journaled in a bearing *492* on a bracket *493* fastened to the top of a vertical rod or stanchion *494* supported from the bed of the machine. The bevel-gear *490* drives a bevel-gear *495* on a horizontal shaft *496* journaled in a bearing *497* on a bracket *498* fastened to the top of a vertical rod or stanchion *499* supported from the bed of the machine. The bevel-gear *495* drives a bevel-gear *500* on a horizontal shaft *501* journaled in a bearing *502* on a bracket *503* fastened to the top of a vertical rod or stanchion *504* supported from the bed of the

ing 31. Fast on the outer end of the shaft 36 is a pulley 38 connected by a belt 39 to a pulley 40 which is driven from an electric motor 41 through gearing in a box 42. The gear-box 42 and motor 41 are mounted at the top of a casing 44 which forms the head of the gang machine and contains the main driving mechanism for the whole series of winding units. Through these connections the conveyor-chain 20 is driven continuously in counterclockwise direction as viewed in Figs. 18 and 20 to carry the cores or bobbins *b* in a straight path along one side of the gang machine above the magazines 2 for the individual spindles; thereafter reversing its course at the rearward side of the machine and then traveling across the delivery end of the hopper, designated generally at H in Fig. 17, where it is supplied with the empty cores for delivery to the various magazines.

As shown in Figs. 3, 18 and 20, certain of the links of the chain 20 have fastened thereto pairs of spaced parallel plates 45 and 46 riveted to their upper and lower elements. The plates 45 and 46 have sockets in their overhanging portions to provide U-shaped pockets 48 for receiving the cores or bobbins *b*. Preferably, as shown more particularly in Fig. 9, a pair of retaining members in the form of U-shaped springs 49 are fastened to the upper and lower plates 45 and 46 with their projecting legs bent into loops at their ends for engaging around the bobbins *b* in the pockets 48 to releasably hold the bobbins therein. The ends of the forked portions of the upper plates 45 may be bent upwardly in prongs 50 which are adapted to engage in under the rounded lower surfaces of the heads *h* of the bobbins *b* to assist in preventing them from sliding out of the pockets 48; in some cases the springs 49 being dispensed with. The assemblies of socketed plates 45 and 46, hereinafter called holders 55 for the bobbins *b*, are spaced apart along the chain 20 with several links intervening therebetween and in advance of each holder 55 in a driver-plate 56, so-called. The driver-plates 56 serve to connect the chain with the selector mechanism adjacent the hopper H to actuate the device to feed bobbins to the holders when the latter are vacant due to delivery of their bobbins to any of the magazines at the winding units. The construction and arrangement of this part of the apparatus is shown in Figs. 18 to 21, inclusive, and described in detail hereinafter.

As previously stated, the cores or bobbins *b* are delivered from the hopper H and fed into the pockets 48 in the holders 55 to initially supply the conveyor 20 and to thereafter fill the empty pockets when vacancies occur therein. The hopper H may be of any preferred form and as herein shown it comprises a relatively large bin having an opening at the top facing toward its side and an inclined bottom wall terminating in a concaved portion at its forward end in which the cores or bobbins *b* gather as they slide down the inclined bottom of the hopper. Means are provided for agitating the cores *b* inside the hopper to cause them to be deposited on a traveling conveyor-belt 57 which runs over a series of pulleys, one of which 58 is driven from a motor 59 supported below the hopper. As these operating parts of the present apparatus are to be described in a continuing application for patent they are not set forth more in detail in the present specification. Suffice it to state that the cores or bobbins *b* are transferred to the upper end of the hopper H in a procession by the traveling belt 57 and there discharged into an inclined

ramp-like raceway 60. The raceway 60 may be comprised of two side plates arranged in parallel spaced relationship to adapt the shanks or barrels of the bobbins *b* to project downwardly between their inner faces with their enlarged heads *h* engaging across the edges of the plates to adapt them to slide downwardly therealong. The hopper H, raceway 60 and other cooperating parts may be supported from a raised framework constructed of angle-irons or timbers and comprising the inclined beams 61 which may also form a part of a scaffold or staging. The staging may have a platform reached by steps on a ramp to enable the cores or bobbins to be dumped into the hopper H by an attendant, but this structure is not herein shown and described as it forms no part of the present invention.

The lower end of the raceway 60 is connected to a shorter raceway or chute 62 by means of clamps 63. The raceway 62 is supported from a standard on a bracket 65 carried by a pair of rods 66 rising from the creel framework and held in the bracket 31, previously described as mounted on the rods or stanchions 30. As shown more particularly in Figs. 17, 18 and 19, the raceway 62 has its bottom wall 67 slotted at 68 to adapt the barrels of the bobbins *b* to project downwardly therethrough and its top is closed by a wall 69 to restrain the bobbins from jumping upwardly therein. The cores or bobbins *b* are thus adapted to slide downwardly through the chute or raceway 62 into position adjacent the side of the conveyor-chain 20 to be transferred into the pockets of the holders 55 on the chain, see Fig. 1. Normally, the bobbins are restrained from sliding out from the open end of the chute 62 by means of a door or gate 70, see Figs. 18 and 19, which surmounts a slide 71 supported to reciprocate horizontally above the base of the bracket 65. As shown in Figs. 18 and 19, the gate 70 is constructed of sheet-metal having a depending portion normally projecting across the open mouth of the raceway 62 with its lateral portion cut away therebeyond toward the right to form an opening reaching to its supporting standard 72. Consequently, when the slide 71 is moved to the left as shown in Fig. 20 the depending closure portion of the gate 70 is carried beyond the lower open end of the raceway 62 to open it. The slide 71 may be constructed of sheet-metal, being constituted as a feeder or pusher having a pointed prow 73 at its forward end adapted to be forced in between the two lowermost cores or bobbins *b* held at the end of the chute 62. As the depending portion of the gate 70 is carried toward the left to free the lowermost bobbin in the raceway 62 during the reciprocation of the slide 71 the forward inclined edge 74 of the pusher 71 will act to plow the lowermost bobbin *b* out of the raceway and force it into the pocket 48 of a holder 55 on the chain 20 in the manner indicated in Fig. 20. Referring to this latter view and Fig. 19, a flat spring 75 fastened to the side of the raceway 62 extends at an inclination outwardly therefrom alongside the chain 20, its function being to act as a guard for contacting the sides of the bobbins *b* beneath their heads to insure that they are seated securely in the pockets 48 of the holders 55. This provides that if the bobbins *b* fail to be forced into the pockets 48 sufficiently to cause them to be grasped by the springs 49 they will be acted upon by the spring 75 to properly seat them in their holders 55. To insure against the jamming of the bobbins *b* in the end of the raceway 62, should they not be

properly seated in the pockets 48 of the holders 55, the left-hand side of the raceway is constituted by a yieldable member 76, see Figs. 18 and 19, pivoted on a pin 78 and normally held in parallel relation to the opposite side of the raceway by a spring 79 coiled around its pivot-pin.

The slide or pusher 71 is mounted on top of a post 80 beneath a cleat 81 screwed to the post and is further supported by two bearing elements 82 and 83, slideable on a horizontal rod 84. The rod 84 is supported at its ends in lugs 85 and 86 rising from the base of the bracket 65. A buffer spring 87 surrounds the end of the rod 84 between the bearing 83 and the lug 86 to take the thrust of the slide 71 when it is drawn rearwardly after its forward reciprocation for feeding a bobbin *b* from the raceway 62 into a holder 55 on the chain 20. The slide or pusher 71 is withdrawn and normally maintained in its rearward position by means of a helical spring 88 having one end hooked to an ear 89 on the slide and its opposite end anchored to an upright arm 90 of an adjustable element 91. The member 91 is fastened to the base of the bracket 65 by means of a pair of screws 92 projecting through a slot 93 in its foot and by releasing the screws the member may be adjusted one way or the other to regulate the tension of the spring 88.

The slide or pusher 71 is adapted to be reciprocated toward the left as viewed in Figs. 18 and 19 through the operation of a slideable latch or bolt 95 carried thereby and engageable with a detent-shoulder 96 on any one of the driver-plates 56 on the chain 20. The latch or bolt 95 is slidably mounted on the pusher or slide 71 in slotted bearings 98 and 99 projecting upwardly therefrom. A helical spring 100 anchored to a cotter-pin 101 held in the bearing 98 is fastened at its opposite end to a cotter-pin 102 held in a pin or stud 103 rising from the latch 95, the spring thus tending to normally slide the latch forwardly to engage its end with the detent-shoulder 96 on a driver-plate 56. The latch or bolt 95 is normally restrained from forward sliding motion by means of a pawl 105 having its pointed toe 106, see Fig. 18, engaged in a notch 107 in the side of the latch. The pawl 105 is pivoted on a pin 108 on the slide 71 and is influenced to engage its toe 106 with the notch 107 in the latch 95 by means of a spring 109 coiled around the pin 108 with one end hooked around the edge of the bearing 98 and its opposite end bearing against the outer end of the pawl.

The means for disengaging the pawl 105 from the latch 95 to cause the latter to be carried into position for engagement with the detent-shoulder 96 on one of the driver-plates 56 comprises a control lever or feeler 110. The feeler 110 is pivoted on a stud 111 screwed into a post 112 surmounting the base of the bracket 65. A spring 113 coiled around the post with one end 114 bent down over the edge of the base of the bracket 65, as shown in Figs. 18 and 19, with its opposite end extended in an arm 115 hooked around over the edge of the lever tends to rock the lever 110 in a clockwise direction as viewed in Fig. 18. At the forward end of the main arm of the lever 110 is an upwardly-bent portion 116 inclined at an angle to adapt it to act as a cam for releasing the pawl 105. For this purpose the pawl 105 has a laterally-extending finger 117 overlying the latch 95 and terminating in a rounded edge with which the inclined cam-portion 116 of the lever 110 engages. The lever 110 is formed with a forwardly-projecting elbow-

shaped arm 118 comprising a tapered extension 120 positioned in alignment with the path of the chain 20 in its lateral course across the front of the hopper H. The lever 110 is supported on a second post 121 and held from vertical play by means of a screw 122 passing through a slot 123 in the main arm of the lever and screwed into the post. The slot 123 serves to limit the forward movement of the lever 110 under the tension of the spring 113.

The feeder or pusher 71 is disconnected from the conveyor-chain 20 after it has been operated to feed a bobbin into one of the holders 55 by releasing the latch or bolt 95 from the driver-plate 56 through the operation of mechanism next described. Depending from the under side of the latch or bolt 95 is a pin 125 slideable in a slot 126 in the slide or pusher 71. Referring to Figs. 20 and 21, the pin 125 is adapted to engage the inclined edge 127 of a cam 128 fastened to the top of a support 129 rising from the base of the bracket 65 and underlying the pusher 71. As the pusher 71 approaches the end of its forward movement to force a core or bobbin *b* into a holder 55 on the chain 20 the pin 125 will ride up the cam-edge 127 to withdraw the end of the latch 95 from the detent-shoulder 96 on the driver-plate 56 as indicated in Figs. 20 and 21. As soon as this release of the latch occurs the spring 88 will act to draw the slide 71 rearwardly, it being noted that above the shoulder 96 the driver-plate 56 is inclined or beveled at 97 so as to clear the end of the latch as the latter is withdrawn. After the latch or bolt 95 has been withdrawn sufficiently to release its forward edge from the detent shoulder 96 on the driver-plate 56 the retraction of the pusher 71 by the spring 88 will carry the pin 125 on the latch into engagement with a pawl-like lever 130 pivoted on the support 129. The lever 130 is pivoted on a stud 131 and biased into position with its end engaging a stop pin 132 by means of a spring 135. The spring 135 is coiled around a screw 136 with the end of its short arm bent down around the side of the support 129 and its opposite longer arm engaging the end of the lever 130. Referring to Fig. 21, as the slide 71 is retracted the pin 125 will engage and ride along the side of the lever 130 until it reaches the limit of its movement as represented by dash-lines in Fig. 21, it being noted that the lever 130 has a greater portion of its length projecting upwardly from its pivoted end in a portion 137 which is beveled off on the side at 138 so that the pin 125 can ride off therefrom after the pusher 71 has been returned to first position shown in Fig. 18. The pin 125 being shown by dotted lines at the right in Fig. 21 as it rides off from the lever 130, the pawl 105 being engaged with the notch 107 in the side 60 of the latch 95 at this juncture to restrain it from sliding forward again. The latch or bolt 95 is thus prevented from further action until the feeler lever 110 has once again been carried forward; see dash lines in Fig. 21, by the absence of a bobbin or core *b* in any one of the holders 55 whereby to cause it to release the pawl 105. To insure that the cores or bobbins *b* carried in the holders 55 will properly engage the projecting arm 120 of the lever 110 to normally prevent its action, means preferably are provided for restraining the conveyor-chain 20 from being diverted in its course during its lateral travel across the front of the hopper H. For this purpose I may provide a guard or track 144, see Fig. 17, on which the rollers 145 on the pins connecting the

links of the chain 20 ride. The rollers 145 riding on the track 144 serve to resist any tendency of the lever 160 to force the cores or bobbins b carried in the holders 55 out of their straight course with the chain 20.

The method of operation of the bobbin-feeding means is explained more in detail hereinafter in connection with the explanation of the functioning of the complete apparatus.

The cores or bobbins b are delivered from the conveyor-chain 20 to the magazines 2 of the winding units upon depletion of the supply therein by the means next described. Referring to Figs. 1, 2 and 3, each magazine 2 is provided with a chute-like casing 150 fastened to the top of the outer slotted upright 6 and reaching upwardly to a point adjacent the conveyor-chain 20; each such chute being constructed of sheet-metal with a front wall 151 and parallel side walls 152 folded inwardly therefrom. Each chute 150 is supported near its upper end by a U-shaped bracket 154, see Figs. 1 and 2, fastened to the end of an arm or bracket 155 secured to a horizontal rod 157 extending the length of the gang machine as a part of the creel framework. Pivotally mounted to swing between the sides of the chute 150 is a balanced lever 160 which normally reaches down into the slotted upright 5 of the magazine 2 to constitute the rearward wall of the chute. The lever 160 further functions as a detector to indicate the absence of a sufficient supply of cores or bobbins b in the magazine.

The detector-lever 160 is preferably formed of sheet-metal with relatively narrow flanges folded forwardly from its sides and a pair of arms 161 reaching forwardly with pins 162 at their ends engaging in slotted bearings 163 in the ends of the arms of the sheet-metal bracket 154. The pivots 162 for the detector-lever 160 are so located as to balance the lever to cause it to swing outwardly into the position shown in Fig. 3 upon release of its lower end from the bobbins in the magazine 2, thereby cooperating with the part 150 to form a closed chute down which the cores or bobbins b may slide upon their delivery from the conveyor-chain 20. With the form of construction shown in Figs. 1 to 3, inclusive, the upper end of the detector-lever 160 is weighted by a thicker strip 164 of metal screwed or riveted thereto and carrying certain instrumentalities adapted to engage a core or bobbin b carried by a holder 55 on the conveyor-chain to discharge it therefrom into the chute for delivery into the related magazine 2. The bobbin-delivering means shown in Figs. 3 to 8 is constructed and arranged as next described.

Referring particularly to Figs. 2 to 8, inclusive, at the upper end of the detector-lever 160 is a triangularly-shaped cam-plate 165 which projects laterally therefrom. The inner straight edge of the cam-plate 165 normally is clear of the bobbins b as they pass thereby when the lever 160 is in the relationship shown in Fig. 2 by the presence of a predetermined number of bobbins in the magazine 2, see also Fig. 5. After a bobbin has been discharged from the magazine 2 to supply the winding spindle, with only two bobbins remaining therein as shown in Fig. 3, the lower end of the lever 160 will be released so that it can swing outwardly to the position shown in Fig. 3. However, such swinging motion is prevented in certain circumstances by means of a detent-lever 166 which is pivoted to the cam-plate 165 and normally held with its end en-

gaging the upwardly-looped side of the track 15 on which the conveyor-chain 20 travels, see Figs. 4 and 5. The lever 166 is pivoted on the top of the cam-plate 165 by means of a pin or stud 167 and is of elbow-shape having a short arm 168 carrying a pin or stud 169 engaging through an arcuate slot 170 in the cam-plate 165. When the detent-lever 166 is in the position shown in Figs. 4 and 5 the upper end of the detector-lever 160 is prevented from swinging toward the right and consequently the cam-plate 165 is maintained out of range of the cores or bobbins b traveling with the chain 20. The purpose of this particular construction is to prevent the lever 160 from being activated at a point where it would interfere with the travel of the cores or bobbins b, but as one bobbin passes clear of the cam-plate 165, see Fig. 6, it will engage with the lever 166 to turn it into the position shown in Fig. 8, thereby permitting the detector-lever 160 to pivot and swing to the position shown in Fig. 3. The lever 160 thus will be activated for releasing the next bobbin b from its holder 55 on the chain 20 to cause it to be delivered down through the closed chute 150 and into the magazine 2.

The swinging motion of the detector-lever 160 may be relatively slow or sluggish, due to its considerable length and the effects of inertia and atmospheric pressure, and therefore it is desirable that the upper end of the lever be released immediately after the passage thereby of one bobbin b so that the cam-plate 165 will assume its operative position in time to act on the next approaching bobbin in the series. As the next bobbin approaches the cam-plate 165 the latter will have been moved to the position shown in Figs. 7 and 8 by the swinging of the lever 160. Consequently, the next bobbin in the series will be engaged by the inclined edge of the cam-plate 165 in the manner shown in Fig. 8, the edge of the cam-plate having a slight depression or concavity in its edge which tends to enclose the barrel of the bobbin b. Thereafter the movement of the bobbin with the conveyor-chain 20 will cause it to ride forward along the remainder of the inclined edge of the cam-plate 165 to finally force it out of the pocket 48 in the holder 55 and discharge it therefrom into the position indicated by dash-lines in Fig. 3. The bobbin thus released from the conveyor-chain 20 will drop by gravity to cause it to slide down the incline of the lever 160 in the manner indicated by full lines in Fig. 3, and as it reaches the lower end of the lever it will tilt the latter rearwardly to carry it back into its initial position shown in Fig. 2. As the newly supplied bobbin b slides down the lever 160 its forward pointed end will seat in the slotted member 6 of the magazine 2 while its rearward heavier end will drop down into the slotted upright 5 of the magazine to rest on the bobbins already contained therein. The head h of this newly supplied bobbin b will remain in contact with the lever 160 to retain the latter in inoperative position until one or more of the underlying bobbins have been transferred from the magazine 2 to supply the spindle 3 of the winding unit. Through this means an adequate supply of bobbins is maintained at all times in the magazine 2. As the lever 160 returns to its normal position shown in Fig. 2 the detent-lever 166 is swung back into operative position under the effect of gravity or, if desired, a suitable spring, not herein shown, may be provided for this purpose to cause the lever to hold the cam-plate 165 until one of the bobbins on the chain 20 has passed

thereby to set it for operation on the next succeeding bobbin in the series.

Figs. 10 to 15 of the present drawings illustrate a modified form of construction of the means for discharging the bobbins from the conveyor-chain 20 to deliver them through the chute into the magazine 2. This particular form of construction of the mechanism is adapted particularly for use with machines in which the conveyor-chain must be elevated to a greater height above the winding units due to certain requirements, such as the provision of more space in the creel. In this latter form of the mechanism the slotted upright 6 of the magazine 2 may have an extension 174 projecting some distance thereabove and the detector-lever 175 may be of greater length than that previously described with its lower end reaching down between the sides of the extension 174. The chute-member 177 may be of substantially the same form and dimensions as previously described, but the bobbin-discharging means is of an alternative form of construction. Since the detector-lever 175 is considerably longer than that previously described it may be subject to swaying or vibration and therefore additional counterbalancing and detention means are applied thereto in accordance with the following description. The lever 175 is pivoted on the bracket 154, previously referred to, by means of a pair of forwardly-extending arms 178 and fastened to one of these arms is an upright arm 179 to which is connected a counterweight 180 through means of a wire link 181. The weight 180 may be of cylindrical form with a forwardly-projecting smaller cylindrical extension 182 which, when the lever 175 is inactive, is adapted to rest on the top of a block 185 fastened at 186 to the rearward portion of the bifurcated bracket 154. The rearward corner of the block 185 is beveled off at 187 and the forward edge of the cylindrical projection 182 of the weight 180 is also rounded or beveled to adapt it to engage the beveled face 187 on the block 185 and slide upwardly thereacross to rest on the top of the block as shown in Fig. 11. In this normal position of the lever 175 the weight 180 acts to counterbalance and restrain the lever from excessive movement. When the detector-lever swings outwardly to the position shown in Fig. 10 the weight 180 acts as a detent to resist movement of the lever 175 until the discharged bobbin b has slid down to its lower end to restore it to first position. During this last movement of the detector-lever 175, the forward projection 182 on the weight 180 will ride up on the top of the block 185 to steady it in its normal position.

In this last-described form of construction of the mechanism the detent-means for initially retaining the detector-lever 175 in its inactive position after its release from the bobbins in the magazine 2 is also somewhat modified from that previously described. Fastened to the upper end of the chute 177 is a bearing-block 190, shown enlarged in Fig. 16 which is a view looking in the opposite direction from that of Fig. 10. The bearing-block 190 is slotted at 191 to straddle the side flange of the chute 177 to which it is riveted at 192. The block 190 is also slotted at 193 to receive an upright lever 194 having an offset finger 195 at its upper end adapted to contact with the bobbins b as they travel with the conveyor-chain 20, see Fig. 13. The contact-lever 194 is pivoted on a crosspin 196 and has a forked lower end engaging one arm 197 of a detent-latch 198. The detent-latch 198 is pivot-

ally mounted within a slot 199 in the block 190 on a vertical pin 200 to adapt it to engage across the edge of the detector-lever 175 to initially restrain the latter from swinging outwardly at its lower end. A bow-shaped spring 201 in the slot 193 of the block 190, see Fig. 16, bears against the lower end of the lever 194 to normally maintain it in position to be engaged by the bobbins as they travel with the conveyor-chain 20. In this last-described form of construction the cam-plate 205 is of substantially the same triangular shape as the cam-plate 165, previously described, except that it is bent or bowed upwardly throughout the greater portion of its width as shown more particularly in Fig. 10. As the bobbins b in the holders 55 on the conveyor-chain 20 travel past the various delivery chutes 177 they will wipe across the contact arm 195 of each lever 194 to rock the latter from one position shown in Fig. 12 to that illustrated in Fig. 13. This rocking motion of the lever 194 will swing the latch 198 to release it from the upper end of the detector-lever 175 to allow the lower end of the latter to swing forwardly to carry the cam-plate 205 into position to discharge the next succeeding bobbin from its holder 55 and deliver it down through the chute 177 into the magazine 2. After the detector-lever 175 has been swung back by the weight of the bobbin passing through the chute its upper edge will slide across the rounded nose of the latch 198, see Figs. 13 and 15, to swing the latch and rock the lever 194 against the action of its spring 201. The detector-lever 175 will thus pass by the latch 198 to cause the latter to retain it in its normal position shown in Figs. 11 and 12 until its lower end has again been released and a bobbin b wiping across the arm 195 of the contact-lever 194 has swung the latter to release the latch.

The complete apparatus operates in the manner next explained. A supply of bobbins b may be placed in the hopper H by any convenient means, for example, through the use of an elevator, escalator, or dumped through a chute opening from the floor above. It has been stated that the bobbins gravitate to the forward concaved bottom of the hopper H and are agitated therein to cause them to ride onto the traveling conveyor-belt 57, by which they are transported to the opposite end of the hopper and delivered into the inclined raceway 60, see Fig. 17. The bobbins slide down the raceway 60 and into the chute or raceway 62 where they may collect in series as indicated more particularly in Fig. 1. At the initial operation of the machine the holders 55 on the conveyor-chain 20 are filled with bobbins b by the repeated action of the pusher 71 in the manner previously explained, it being understood that until all the holders 55 are filled the feeler-lever 110 will be released to the position indicated by the dash-lines in Fig. 21 to cause continuous reciprocation of the slide or pusher 71. The bobbins are thus fed continuously into the holders 55 and in the meantime certain bobbins may be discharged from the conveyor and delivered into the magazines 2 for the several units of the winding machine. As the magazines 2 are filled by the delivery of the bobbins from the conveyor-chain 20 the holders 55 on the chain 20 will be re-supplied with fresh bobbins through the continuous operation of the feeding mechanism embodying the slideable pusher 71. During the operation of the winding units as the wound bobbins are doffed there-

from, fresh empty bobbins will be transferred to the winding spindles from the magazines 2 and when the supply of bobbins in each magazine is depleted new bobbins will be delivered thereto from the chain 20 as required to replenish their supply. As the method of discharging the bobbins from the holders 55 on the conveyor-chain 20 and delivering them to the magazines 2 has been described quite fully in connection with the detailed explanation of the means employed for this purpose, it is considered unnecessary to enlarge the description herein. Suffice it to state that as the supply of bobbins in each magazine 2 is depleted to a predetermined extent, for example, down to two remaining bobbins, the detector-lever 160 in the first described form of construction, or 175 in the second form, is released. Thereupon, the release of the detent-means comprising the lever 166 in the first-described form, or the latch 198 in the second form, by the travel of a bobbin along its contact arm will execute the release of the detector-lever 160 or 175 to cause its upper end to swing into active position. The cam-plate 165 or 205, as the case may be, will then engage the next succeeding bobbin in the series on the chain 20 to eject it from its holder 55 to discharge it into the chute 150 or 177 and deliver it to the magazine 2.

It has been explained that the pin 125 on the under side of the latch 95 engages with one side of the lever 130 to hold the latch disengaged from the driver-plate 56 during the retraction of the pusher 71 after its forward stroke. The pin 125 will eventually ride off from the up-standing flange on the lever 130 so that it will be released from the latter, and prior to this release the pawl 105 will be engaged with the notch 107 in the latch 95 to restrain the latter from forward movement until another vacancy in the holders 55 releases the lever 110 to cause it to disengage the pawl from the latch. When the pusher 71 is carried forward through the engagement of the latch 95 with one of the driver-plates 56 on the conveyor-chain 20 the pin 125 on the under side of the latch will pass on the opposite side of the lever 130 from that traversed during its travel in the reverse direction. The pin 125 will slide along this side of the lever 130 and rock it slightly against the action of its spring 135, see dash-lines in Fig. 21, eventually coming into engagement with the edge 127 of the cam 128. After the pin 125 has moved beyond the end of the lever 130 and the latch 95 has been withdrawn from the shoulder 96 on the driver-plate 56 by the action of the cam 128, as indicated in Fig. 21, the pin 125 will be in position to again ride across the opposite side of the lever 130 to retain the latch disengaged from the chain 20 until the pawl 105 has once more engaged its notch to restrain it from forward movement.

It will be observed by reference to the foregoing specification that the present invention provides a highly automatic apparatus for supplying bare cores or empty bobbins to a winding machine or the like embodying a plurality of units. The device operates without manual control or human effort, it being only necessary to fill the hopper with a plentiful supply of cores or bobbins which are fed continuously therefrom to the conveyor, and from which they are discharged and delivered into the magazines of the several winding units as required by depletion of the supply of bobbins therein. Ma-

chines embodying bobbin-donning and -doffing means are therefore rendered capable of operating continuously without attention on the part of an operator except in some instances to piece up broken ends on rare occasions. The present apparatus is applicable to various types of winding machines wherein a plurality of stationary units are arranged in series; or it may be adapted for supplying cores to a plurality of winding units traveling in a procession relatively to the supplying means.

While the apparatus is herein shown and described as embodied in a preferred form of construction with certain slight modifications in its mechanical details, it is to be understood that further changes may be made in the form and arrangement of the parts of the device without departing from the spirit or scope of the invention. Therefore, without limiting myself in this respect, I claim:

1. In a winding machine comprising a plurality of individual winding units, a bobbin-supplying mechanism including a conveyor for delivering empty bobbins to the several winding units for winding yarn thereon, means for effecting relative movement between the conveyor and the winding units, a magazine at each winding unit for holding a plurality of empty reserve bobbins, detector means permanently located at each winding unit and extending from the conveyor into the respective magazine for engagement with the bobbins therein, said detector means being releasable from the bobbins upon depletion of the supply of reserve bobbins, and means operative by said detector means upon the release thereof for delivering bobbins from the conveyor to the magazines.

2. In a winding machine comprising a plurality of winding units each having a magazine for holding a plurality of empty reserve bobbins, a conveyor for delivering the bobbins to the magazines of the several units, means for effecting relative movement between the conveyor and the winding units, detector means permanently located at each winding unit and reaching from the conveyor into the respective magazine for engagement with the bobbins therein, said detector means being releasable from said engagement upon depletion of the supply of reserve bobbins in the magazine, and means operated by said detector means upon its release for delivering bobbins from the conveyor to the magazines as required to maintain a supply therein.

3. In a winding machine comprising a plurality of winding units, a magazine at each winding unit for containing a supply of empty reserve bobbins, a conveyor movable relatively thereto, detector means permanently located adjacent each winding unit and suspended above each magazine and reaching thereinto to engage with the bobbins therein, said detector means being releasable by depletion of the supply of reserve bobbins in the magazine, and means operated by said detector means upon its release for delivering bobbins from the conveyor to the magazines as required to maintain a supply of empty bobbins therein.

4. In a winding machine comprising a plurality of winding units, a magazine at each winding unit for containing a supply of empty reserve bobbins, a conveyor for holding empty bobbins, means for effecting relative movement between the conveyor and the winding units, a chute at each winding unit opening adjacent

the conveyor and leading into the magazine, and detector means permanently located at each magazine and engageable with the bobbins therein, said detector means being releasable upon depletion of the supply of empty reserve bobbins in the magazine to discharge a bobbin from the conveyor to cause it to slide down the chute into the magazine.

5. A winding machine comprising a plurality of winding units each having means for donning empty bobbins in position for winding including a magazine, bobbin-supplying mechanism including means for conveying bobbins to the winding units, means for effecting relative travel between the conveying means and the winding units, detector means permanently located at each magazine and engageable with the bobbins therein, said detector means being releasable by depletion of the supply of empty bobbins in the magazines, and means operative by said detector means upon its release for delivering bobbins from the conveying means to the magazines as required to maintain a supply of reserve bobbins therein.

6. In a winding machine comprising a plurality of winding units and means for donning empty bobbins at the winding units including a magazine for each unit, detector means permanently located at each magazine, said detector means being normally held inoperative by engagement with the bobbins in the magazines and releasable therefrom upon depletion of the supply therein, bobbin-supplying means for releasably holding a plurality of empty bobbins, and means operative by the detector means upon its release from the bobbins by depletion of the supply of empty reserve bobbins in any of the magazines to deliver bobbins thereto from the bobbin-supplying means to maintain a supply of reserve bobbins therein.

7. In a winding machine comprising a plurality of winding units each having a magazine for holding a supply of empty reserve bobbins, a conveyor for holding a supply of empty bobbins, means for operating the conveyor to travel the bobbins relatively of the magazines, detector means permanently located at each magazine and engageable with the bobbins for indicating depletion of the supply of reserve bobbins therein, said detector means being releasable from the bobbins for movement thereafter, and means operative by said movement of the detector means to release the empty bobbins from the conveyor and deliver them to the magazines as required to maintain a supply of empty bobbins therein.

8. In a winding machine comprising means for donning an empty bobbin and winding yarn thereon, a magazine for holding a supply of empty reserve bobbins, means for transferring a bobbin from the magazine to the winding means, a detector permanently located at the magazine and normally maintained in inoperative position by engagement with the bobbins in the magazine and releasable from the bobbins upon depletion of the supply therein, means for conveying empty bobbins to the magazine, and means operative by said detector when it is disengaged from the bobbins to release a bobbin from the conveying means to deliver it to the magazine to renew the supply therein.

9. In a winding machine comprising means for holding empty bobbins and winding yarn thereon, a magazine for containing a supply of reserve bobbins for delivery to the holding means

of the winding machine, bobbin-supplying means for holding a plurality of empty bobbins, means for effecting relative movement between the bobbin-supplying means and the winding means, and a detector permanently located at the magazine and normally held inoperative by engagement with the bobbins when a predetermined number of empty bobbins are present in the magazine said detector being releasable upon depletion of the supply of bobbins in the magazine, and means operative by said detector upon its release to discharge a bobbin from the bobbin-supplying means to deliver it to the magazine.

10. In a winding machine comprising a plurality of winding units for mounting empty bobbins and winding yarn thereon, a magazine at each winding unit for containing a supply of empty reserve bobbins for transfer to the mounting means, a conveyor carrying holders for empty bobbins, means for traveling the conveyor in a closed course relatively to the several winding units, a detector permanently located at each magazine and normally restrained from operation by engagement with the reserve bobbins therein, and means operative by said detector upon its release by the bobbins in the magazine to deliver bobbins from the conveyor to the magazines as required by the depletion of the supply therein.

11. In a machine for winding yarn on bare cores, the combination of a magazine for holding a reserve supply of cores, a traveling conveyor for carrying cores to the magazine, said conveyor embodying means for gripping the cores to convey them thereby, a pendant lever having one end normally positioned in the magazine for engagement by the cores and its opposite end adjacent the conveyor, and means carried by said lever for discharging cores from the conveyor to deliver them to the magazine when said lever is released by depletion of the supply of cores in the magazine.

12. In a winding machine for winding yarn on bare cores, a magazine for holding a reserve supply of cores, a conveyor having pockets for individually containing a plurality of cores, means for traveling the conveyor to transport the cores to the magazine, a lever pivoted above the magazine with its lower end adapted to be engaged by the cores contained therein, and means carried by the upper end of the lever for engaging a core and discharging it from the pocket in the conveyor to deliver it to the magazine when said lever is released by depletion of the supply of cores in the magazine.

13. In a machine for winding yarn on bare cores or empty bobbins, the combination of a magazine for containing a reserve supply of cores, a conveyor having means for transporting a plurality of cores, means for traveling the conveyor, a pendant lever arranged with its lower end in the magazine to adapt it to be restrained from movement by the cores therein, a cam at the upper end of the lever, detent means for initially restraining the lever from movement when its lower end is released by depletion of the supply of cores in the magazine, said detent means being releasable by the travel of one of the cores on the conveyor to cause the lever to release a succeeding core therefrom to deliver it to the magazine.

14. In a machine for winding yarn on bare cores or bobbins, the combination of a magazine for containing a reserve supply of cores, a travel-

ing conveyor for transporting the cores relative to the magazine, detector-means normally held inactive by a supply of cores in the magazine, detent means for initially restraining said detector-means from action when first released by depletion of the supply of cores in the magazine, said detent means being released by the passage thereby of a bobbin moving with the conveyor, and means operative by said detector-means upon release by the detent means to discharge the next succeeding bobbin from the conveyor to deliver it to the magazine.

15. In a machine for winding yarn on bare cores or bobbins, the combination of a magazine for containing a reserve supply of bobbins, a traveling conveyor for transporting bobbins relatively to the magazine, a detector normally held inactive by a supply of bobbins in the magazine, means operative by said detector to discharge a bobbin from the conveyor to deliver it to the magazine, and detent means for initially restraining the detector from action after it is released by depletion of the supply of bobbins in the magazine, said detent means being releasable by the passage thereby of a bobbin traveling with the conveyor to cause the detector to act on the next succeeding bobbin traveling with the conveyor.

16. In a machine for winding yarn on bare cores, a magazine for containing a reserve supply of cores, a traveling conveyor for transporting cores to the magazine, a lever pivoted above the magazine with its lower end engageable by the bobbins therein, and cam means at the upper end of the lever for engaging a core to discharge it from the conveyor when the lower end of the lever is released by depletion of the supply of cores in the magazine, said lever acting as a support for the core to adapt it to slide downwardly thereon to enter the magazine and return the lever to inoperative position.

17. In a machine for winding yarn on empty bobbins, the combination of a magazine for containing a supply of reserve bobbins, a traveling conveyor having pockets for receiving the bobbins to transport them to the magazine, a chute leading from the conveyor into the magazine, a lever pivoted above the magazine with its lower end engageable by the bobbins in the magazine to restrain it from action, and cam means at the upper end of the lever adapted to engage a bobbin carried by the conveyor to discharge it from its pocket and cause it to slide down the chute into the magazine, said lever being balanced to cause the weight of the bobbin to return it to initial position and restrain it from further action as the bobbin enters the magazine.

18. In a machine for winding yarn on empty bobbins, the combination of a magazine adapted to hold a plurality of bobbins one above another to form a reserve supply, a traveling conveyor for transporting bobbins relatively to the magazine, an inclined chute having its open top adjacent the conveyor and its lower end adjacent the magazine, a lever pivoted above the magazine with its longer arm extended downwardly into the magazine for engagement by the bobbins held therein and its shorter arm projecting alongside the open upper end of the chute, and means operative by said lever to discharge a bobbin from the conveyor to cause it to enter the chute to slide downwardly into the magazine.

19. In a machine for winding yarn on bare cores, the combination therewith of a magazine for holding a reserve supply of cores, a traveling

conveyor for carrying cores to the magazine, a detector normally held inactive by a supply of cores in the magazine, means operative by said detector to discharge a core from the conveyor to deliver it to the magazine when the supply therein becomes depleted, a detent-lever for initially preventing action of the detector when first released by depletion of the supply of cores in the magazine, said detent-lever being releasable by the passage of a core traveling with the magazine to cause action of the detector on the next following core, and means to return the detent lever to position to restrain the detector from action after the latter has discharged a core from the conveyor.

20. A bobbin-supplying device for winding machines comprising a hopper for containing a plurality of empty bobbins, a conveyor travelable in a closed course adjacent said hopper and provided with pockets for receiving bobbins therefrom, means for feeding the bobbins in series from said hopper, a raceway for delivering the bobbins from the hopper to the conveyor, a feeler for indicating absence of the bobbins in the pockets of the conveyor, and means operative by the feeler to force a bobbin out of the raceway and into an empty pocket on the conveyor.

21. A bobbin-supplying device for winding and like machines comprising a hopper for containing a plurality of empty bobbins, a conveyor travelable in a closed course adjacent the hopper, said conveyor provided with pockets for holding the empty bobbins, a raceway leading from the hopper, means for feeding the bobbins from the hopper through the raceway comprising a reciprocable element for engaging a bobbin and transferring it into a pocket on the conveyor, a feeler for indicating the absence of bobbins in any of the pockets of the conveyor, and means operated by said feeler to reciprocate the feeding means.

22. In a bobbin-supplying device for winding and like machines, a hopper for containing a plurality of empty bobbins, a raceway leading from the hopper, a conveyor-chain having pockets for releasably holding the bobbins, means for traveling the conveyor-chain in a closed course adjacent the end of the raceway, means for feeding the bobbins in series from the hopper through the raceway, a pusher adapted to engage the endmost bobbin in a series fed from the hopper into the raceway to project it into a pocket on the conveyor-chain, and means operative by the traveling motion of the chain to actuate the pusher to supply bobbins to the empty pockets on the conveyor.

23. A bobbin-supplying device for winding and like machines comprising a hopper for containing a plurality of empty bobbins, a conveyor carrying pockets for a plurality of bobbins, means for traveling the conveyor in a closed course adjacent the hopper, a raceway for feeding bobbins in a series from the hopper, a pusher reciprocable to engage the endmost bobbin in a series to transfer it from the raceway into a vacant pocket on the conveyor, means to reciprocate said pusher, and a feeler operative to connect the pusher to the reciprocating means upon indication of vacancy in any of the pockets on the conveyor.

24. In a mechanism for supplying empty bobbins to a winding or like machine, a hopper for containing a plurality of bobbins, a raceway leading from the hopper, a traveling conveyor carrying holders for receiving the bobbins from the raceway, means to travel the conveyor in a closed course adjacent the raceway, means for feeding

the bobbins from the hopper into the raceway, a gate for closing the end of the raceway adjacent the conveyor, means for opening the gate to feed a bobbin from the raceway into a holder on the conveyor, and means operative by the absence of a bobbin in any of the holders to open the gate and transfer a bobbin from the raceway into the vacant holder.

25. In a bobbin-supplying mechanism for winding and like machines, a hopper for containing a supply of bobbins, a raceway for feeding the bobbins from the hopper, a conveyor having pockets for containing the bobbins, means for traveling the conveyor in a closed course past the end of the raceway, a gate for closing the end of the raceway, a positively acting pusher for sliding the bobbins out of the raceway and into the pockets on the conveyor, and means operative to open the gate and actuate the pusher as an empty pocket registers with the end of the raceway.

26. In a bobbin-supplying mechanism for winding and like machines, a hopper for containing bobbins, a raceway for feeding the bobbins from the hopper, a conveyor traveling in a closed course adjacent the end of the raceway and having pockets for receiving the bobbins therefrom, a pusher for positively ejecting the bobbins singly from the raceway to enter them in the pockets on the conveyor, a slide for operating the pusher, and means for connecting the slide with the conveyor to cause it to actuate the pusher when a vacancy occurs in any of the pockets.

27. In a bobbin-supplying mechanism for winding and like machines, a hopper for containing bobbins, a raceway for feeding the bobbins from the hopper, a conveyor having pockets for receiving bobbins fed from the raceway, means for traveling the conveyor past the end of the raceway, a reciprocable pusher for forcing the bobbins out of the raceway and into the pockets, a feeler normally engaged by bobbins held in pockets on the conveyor, and means operative upon release of the feeler due to absence of a bobbin in a pocket on the conveyor to actuate the pusher to force a bobbin out of the raceway and into the empty pocket on the conveyor.

28. In a bobbin-supplying mechanism for winding and like machines, a hopper for containing bobbins, a raceway for feeding the bobbins from the hopper, a conveyor carrying pockets for receiving the bobbins from the raceway, means for traveling the conveyor with respect to the raceway, a reciprocable pusher for forcing the bobbins out of the raceway and into empty pockets on the conveyor, a feeler normally restrained from action by bobbins in the pockets of the conveyor, and means operative by release of the feeler upon the occurrence of a vacancy in the pockets on the conveyor to connect the conveyor to actuate the pusher.

29. In a device for supplying bobbins to winding and like machines, a hopper for containing bobbins, a raceway for feeding the bobbins in series from the hopper, a conveyor carrying

pockets for receiving the bobbins from the raceway, means for traveling the conveyor, a pusher for engaging a bobbin in the raceway to force it therefrom into a pocket on the conveyor, a latch for connecting the pusher for movement by the conveyor, and a feeler normally held inoperative by bobbins in the pockets on the conveyor and releasable on occurrence of an empty pocket to actuate the latch to cause movement of the pusher to eject a bobbin from the raceway into an empty pocket on the conveyor.

30. In a machine for winding yarn on bare cores or bobbins, the combination of a magazine for containing a reserve supply of cores, a traveling conveyor for transporting the cores to the magazine, holders on the conveyor for individually receiving the bobbins, means at the magazine for releasing the bobbins individually from the holders on the conveyor, and means operative by the movement of a bobbin past said releasing means to cause it to act to discharge the next succeeding bobbin from the conveyor to deliver it to the magazine.

31. In a machine comprising a plurality of units for winding yarn on bare cores or bobbins, the combination of a chute located adjacent each winding unit for feeding bobbins thereto, a traveling conveyor having holders for transporting the bobbins to the several chutes, means for releasing the bobbins individually from the holders at the chutes, and means operative by a bobbin passing the releasing means to cause the latter to act to release the next succeeding bobbin carried by the conveyor to deliver it to the chute.

32. In a machine comprising a plurality of winding units, a chute at each winding unit for feeding the bobbins thereto, a conveyor having pockets for individually holding the bobbins, means for traveling the conveyor to transport the bobbins to the several chutes at the winding units, means for discharging the bobbins individually from the pockets on the conveyor, detent means for normally preventing operation of the bobbin-discharging means, and means operative by the passage of a bobbin past the detent means to release it from the discharging means and cause the latter to deliver the next succeeding bobbin into the chute.

JOHN A. MOLLOY.
